UNITED STATES PATENT OFFICE

163,345

EMBLEM

Tessie Wiggins, New Rochelle, N. Y.

Application October 16, 1950, Serial No. 12,581

Term of patent 7 years

(Cl. D29—2)

To all whom it may concern:

Be it known that I, Tessie Wiggins, a citizen of the United States, residing at New Rochelle, in the county of Westchester and State of New York, have invented a new, original, and ornamental Design for an Emblem, of which the following is a specification, reference being had to the accompanying drawing, forming part thereof.

Figure 2 is a vertical sectional view thereof, taken substantially on the plane of the line 2—2 of Figure 1 looking in the direction of the arrows.

The dominant features of my design are shown in full lines.

The back of my emblem is conventionally plain.

I claim:

The ornamental design for an emblem, as shown and described.

TESSIE WIGGINS.
